UNITED STATES PATENT OFFICE.

SAMUEL A. SHELTON, OF MARSHFIELD, MISSOURI.

MUSIC-BOOK HOLDER.

SPECIFICATION forming part of Letters Patent No. 642,725, dated February 6, 1900.

Application filed May 18, 1899. Serial No. 717,350. (No model.)

To all whom it may concern:

Be it known that I, SAMUEL A. SHELTON, a citizen of the United States, residing at Marshfield, in the county of Webster and State of Missouri, have invented a new and useful Music-Book Holder, of which the following is a specification.

The invention relates to improvements in music-book holders.

10 The object of the present invention is to improve the construction of music-holders and to provide a simple, inexpensive, and efficient device adapted to be readily applied to a piano or organ and capable of holding book and sheet music and of being readily adjusted to arrange it out of the way, so that music may be changed or the leaves of a book freely turned.

15 The invention consists in the construction and novel combination and arrangement of parts hereinafter fully described, illustrated in the accompanying drawings, and pointed out in the claims hereto appended.

20 In the drawings, Figure 1 is a perspective view of a music-holder constructed in accordance with this invention. Fig. 2 is a side elevation, the music-engaging arm being thrown back out of the way. Fig. 3 is a longitudinal sectional view. Fig. 4 is a detail 25 view of the base-plate or body.

Like numerals of reference designate corresponding parts in all the figures of the drawings.

1 Designates a base-plate or body designed 30 to be secured to a piano or organ and provided at its upper portion with perforated ears or lugs 2, in which is arranged a shaft or pintle 3, forming a fulcrum for a spring-actuated music-engaging arm 4. The plate or 35 body 1 may be of any desired configuration, and it is provided at its center with a perforation 5 for the reception of a screw 6 for securing it to a piano or organ. The perforated ears or lugs 2 are located at opposite 40 sides of the base or body 1, and the transverse shaft is provided at its center with an opening 8, forming a socket for the inner or lower end of the music-engaging arm 4, which is secured within the said opening by a clamp- 45 ing-screw 9. The screw 9, which is mounted 50 in a suitable perforation of the shaft or pin-

tle, detachably secures the music-engaging arm 4 to the same.

The arm 4, which carries an adjustable transverse bar or member 10, is held in engagement with a book or piece of sheet-music by a spring 11, having a central loop 12 and provided with opposite coils 13, the terminals of the spring bearing against the upper portion of the base in the space between the perforated ears or lugs. The base or body 1 may be mounted on a piano or organ in a horizontal or an inclined position, and as the screw 9 is disposed between the two sets of coils of the spring the latter will detain the pintle or shaft 65 in the perforated lugs or ears while the said screw 9 is in position, but as soon as the screw is removed the shaft or pintle may be withdrawn.

One end of the shaft or pintle is provided 70 with a disk or head 14, having notches 15 and forming a ratchet-wheel which is adapted to be engaged by a pivoted pawl or locking-lever 15, fulcrumed between its ends at one side of the base or body and having a 75 tooth 16 to engage the teeth or shoulders of the ratchet-head. The other end of the pawl or lever is flattened, as shown, to provide a convenient finger-piece, so that the pawl or lever may be readily operated to engage the 80 grip and disengage it from the ratchet-head. The locking lever or pawl is preferably mounted on a screw 17; but any other suitable form of pivot may be provided.

The transverse bar or member 10, which 85 extends laterally from opposite sides of the music-engaging arm, is adapted to bear against the two open leaves of a book or a piece of sheet-music, and it is provided at its center with an opening 18 for the reception 90 of the arm 4, to which it is adjustably secured by means of a clamping-screw 19. The clamping-screw 19, which is mounted in a threaded perforation of the transverse bar or member, engages the face of the bar or arm 4 and secures the said bar or member 10 at the desired adjustment. The transverse bar or member may be moved inward or outward on the arm 4 to raise and lower it, whereby a music-book or piece of sheet-music may be 100 engaged at the proper point. When it is desired to release the music, the arm 4 is swung

backward and is held in such position by the locking pawl or lever, so that the music may be changed or the leaves of a book freely turned.

5 The invention has the following advantages: The music-holder, which is adapted to engage a music-book or a piece of sheet-music, is simple and comparatively inexpensive in construction and may be readily applied to a piano or organ. It is capable of being readily adjusted, so that it will engage the music properly, and it may be readily locked out of such engagement, so that the music can be changed or the leaves of a book 10 freely turned.

15 Changes in the form, proportion, size, and the minor details of construction within the scope of the appended claims may be resorted to without departing from the spirit or sacrificing any of the advantages of this invention.

20 What is claimed is—

1. A music-holder comprising a base provided with opposite lugs, a shaft or pintle journaled thereon and provided between the 25 same with a socket or opening, and having a ratchet-head at one end, a spring disposed on

the shaft or pintle and having a loop or engaging portion, an arm receiving the loop or engaging portion and detachably secured in the socket or opening, and a pawl engaging 30 the ratchet-head, substantially as described.

2. A music-holder comprising a base having opposite perforated lugs at its upper end, a fastening thumb-screw passing through the base, a shaft or pintle journaled on the lugs 35 and having a ratchet-head at one end, a locking pawl or lever mounted on the base and arranged to engage the ratchet-head, a music-engaging arm having an adjustable transverse bar, mounted on the shaft or pintle between the lugs and a coiled spring disposed on the shaft or pintle, said spring having an intermediate loop which engages the music-engaging arm, substantially as described.

30 In testimony that I claim the foregoing as my own I have hereto affixed my signature in the presence of two witnesses.

SAMUEL A. SHELTON.
